UNITED STATES PATENT OFFICE.

RAYMOND N. EHREHART, OF EDGEWOOD PARK, PENNSYLVANIA, ASSIGNOR TO WESTINGHOUSE ELECTRIC & MANUFACTURING CO., A CORPORATION OF PENNSYLVANIA.

CONDENSER.

1,406,356.

Specification of Letters Patent. Patented Feb. 14, 1922.

Application filed October 1, 1917. Serial No. 194,177.

To all whom it may concern:

Be it known that I, RAYMOND N. EHREHART, a citizen of the United States, and a resident of Edgewood Park, in the county 5 of Allegheny and State of Pennsylvania, have made a new and useful Invention in Condensers, of which the following is a specification.

This invention relates to condensers and 10 has for an object to produce an improved surface condenser in which means are employed for effectively and efficiently directing the fluid to be condensed into the nest of tubes of the condenser.

15 A further object is to produce a surface condenser in which the baffles are so arranged within the nest of cooling tubes as to prevent condensate from dropping from upper and onto lower cooling tubes of the nest, and in which this is accomplished without 20 rendering any of the tubes less effective as steam condensing agents and without restricting the passage of the fluid to be condensed through the nest.

25 A further object is to produce a condenser and system of baffles therefor in which the steam is directed through the nest of tubes in paths of natural flow and in which the baffles are so arranged as to cause water of 30 condensation to pass through a zone of incoming steam in its travel toward the condensate offtake port.

These and other objects are attained by 35 means of apparatus embodying the features herein described and illustrated in the drawings accompanying and forming a part hereof.

In the drawings: Fig. 1 is a diagrammatic sectional view of a radial flow condenser and 40 illustrates the approximate direction of normal steam paths through the nest of tubes of the condenser.

Fig. 2 is a diagrammatic sectional view of a condenser embodying my invention.

45 Fig. 3 is a corresponding view of a modified form of my invention.

Condensers are frequently provided with baffles for directing the steam to be condensed through the nest of tubes and for so 50 disposing of the condensate as to prevent condensate from upper tubes of the nest from dropping onto lower tubes of the nest and thereby detrimentally affecting the ef-

iciency of the lower tubes. Such baffles are generally so arranged that the steam is 55 forced to follow a circuitous path through the nest of tubes and in addition to this, the arrangement of the baffles is often such as to restrict the path of flow to thereby occasion a detrimental pressure drop between 60 the inlet to the condenser and the coldest portion of the nest of tubes.

My invention contemplates a condenser and a system of baffles by which steam delivered to the condenser is so directed through 65 the tubes and toward an air offtake, located within the nest of tubes, that all the steam is effectively and efficiently condensed without occasioning an objectionable drop in pressure between the inlet to the condenser 70 and the point of air offtake within the nest of tubes. In addition to this, baffles are arranged to so dispose of the condensate as to prevent it from dropping onto lower tubes 75 of the condenser.

In Fig. 1, I have illustrated diagrammatically a radial flow condenser. The nest of tubes 12 is substantially surrounded by a steam space 13 which communicates with the condenser inlet 14. The air offtake 15 80 is so arranged that its inlet is located well within the nest of tubes, as for example, at the center of the nest 12. The steam to be condensed enters the nest of tubes from points around the nest and flows inwardly 85 toward the point of complete condensation, or toward the air offtake port. The arrows in Fig. 3 illustrate the general direction of steam flow through the nest of tubes 12.

In Fig. 2, I have illustrated an embodiment of my present invention in which the air offtake port is located substantially centrally within the nest of tubes and in which the baffles radiate from the air offtake port and at the same time are so arranged as to 95 protect lower tubes of the nest from condensate dropping from tubes located above them. The shell 16 of the condenser illustrated in Fig. 2 is substantially cylindrical, and is provided with an inlet port 17 located 100 above a substantially cylindrical nest of tubes 18, which is enclosed within the shell. As illustrated the nest of tubes 18 is eccentrically located with relation to the cylindrical shell 16 and is so arranged as to provide a steam space, which entirely surrounds 105

the nest, but which diminishes in cross-sectional area toward the bottom of the shell, or toward a condensate well 19 with which the shell is provided.

5 As shown, the steam space is substantially crescent shape, with the widest portion communicating with the inlet 17 and the horns extending toward the condensate well 19. The tubes of the nest are so located that the steam space while substantially surrounding the entire nest does not have free and unobstructed communication with the condensate well since lower tubes of the nest are so spaced with relation to the shell, as to prevent steam from flowing directly into the condensate well without first having been subjected to sufficient cooling surface to be condensed.

20 The paths of normal steam flow in the condenser illustrated in Fig. 2 are substantially radial and consequently by providing substantially radial baffles the normal path of steam flow is not sufficiently affected by the baffles to obstruct the flow or to lengthen 25 the path of flow through the nest.

25 In Fig. 2, I have shown six baffles which extend inwardly from the periphery of the nest of tubes. The upper baffles 20^a and 20^b are inclined downwardly toward the interior of the nest and are so arranged that they deliver the condensate, collected by them, onto baffles 20^c and 20^d respectively. These last mentioned baffles are inclined downwardly from the interior to the periphery of the nest of tubes. An intermediate baffle 20^e is located between the baffles 20^a and 20^c and a similar baffle 20^f is located between the baffles 20^b and 20^d. Both these baffles are inclined downwardly so as to 30 discharge condensate collected by them into the steam space. With the arrangement described, the baffles radiate from a point adjacent to the inlet of an air offtake 21 with which the condenser is provided and substantially all of the condensate collected by the baffles is delivered into the steam space 18 so that it must travel through incoming steam in its passage to the condensate well 19. The condensate well is, of course, provided with a condensate discharge port, and the air offtake 21 communicates with or extends through an air offtake port formed in the shell 16 of the condenser.

50 Under some conditions the velocity of the incoming steam may vary the paths of flow through the nest of cooling tubes within the condenser. For example, the steam entering the condenser may have sufficient velocity to cause a large portion of the steam 55 to pass directly downward into the nest of tubes instead of being equally distributed around the nest of tubes. Where this is encountered it is desirable to locate the inlet to the air offtake somewhat below the center of the nest of tubes and to so arrange

the baffles as to accommodate the normal flow of steam under the conditions encountered.

5 In Fig. 3, the air offtake extends well below the center of the cylindrical nest of tubes and the nest is provided with but four baffles. These baffles radiate from points adjacent to the inlet to the air offtake and are so arranged that the condensate collected by the upper baffles is delivered onto the lower baffles and is discharged by these baffles into the steam space surrounding the nest of tubes. With the exception of the baffles, I have indicated the different elements of the condenser shown in Fig. 3 by the same numerals as those employed in Fig. 2, but I have distinguished the numerals of Fig. 3, by means of a prime mark.

While I have described and illustrated but two embodiments of my invention, it will be apparent to those skilled in the art that various changes, modifications, additions and omissions may be made in the apparatus illustrated without departing from the spirit and scope of my invention, as set forth by the appended claims.

What I claim is:

1. A condenser including a nest of tubes, an air offtake port located well within the nest of tubes, and baffles radiating substantially from the air offtake port.

2. In a condenser, a shell, a nest of tubes therein spaced away from the shell, a non-condensable fluid offtake extending into said nest of tubes, and baffles radiating through the nest of tubes from a point near the non-condensable fluid offtake.

3. In a condenser, a shell, a nest of tubes and upper and lower baffles within the nest of tubes and arranged to direct the steam along paths corresponding to the natural path of steam flow, each upper baffle having its lower edge arranged vertically above the surface of a lower baffle so that the latter receives condensate from the upper baffle.

4. In a condenser, a nest of tubes located within the condenser shell and substantially surrounded by fluid delivery space, which communicates with the fluid inlet of the shell, baffles arranged within said nest to form converging fluid passages through the nest which communicate with said space, and a non-condensable fluid offtake having its inlet well within the nest of tubes and substantially at the point of convergence of said passages.

5. In a condenser, a nest of cooling elements, a non-condensable fluid offtake port located within the nest of cooling elements near the point of convergence of the normal paths of flow of fluid to be condensed, and baffles extending through said nest from a point adjacent to the non-condensable fluid offtake port.

6. In a condenser, a shell, a nest of tubes within said shell and having a stem space substantially surrounding said nest of tubes, an air offtake located well within the nest of tubes, and baffles radiating through the nest from a point adjacent to the air offtake.
7. In combination in a condenser, a shell having an inlet and a condensate outlet, a nest of tubes so located within the shell as to provide a steam space substantially surrounding the nest of tubes but decreasing in cross sectional area toward the condensate outlet, an air offtake located well within the nest of tubes, and baffles extending from the periphery of the nest inwardly toward the air offtake for dividing the nest into segmental sections.
8. In combination with a condenser, a shell having an inlet port located on the upper side thereof, and a condensate discharge port located on the lower side thereof, a nest of tubes so located within the shell as to provide a steam space communicating with the inlet port and extending substantially around the nest of tubes but decreasing in area toward the condensate discharge port, baffles arranged within said nest so as to provide convergent fluid passages which communicate with the steam space and an air offtake having its inlet well within the nest of tubes and substantially at the point of convergence of said passages.
9. In combination in a condenser, a shell having an inlet port formed therein, a nest of tubes so located within the shell as to provide a steam space between the nest and shell which communicates with the inlet, an air off-take having its inlet well within the nest of tubes, and baffles located within the nest of tubes and so arranged as to deliver condensate into said steam space and to deliver non-condensable gases to said air off-take.
10. In combination in a condenser, a shell having an inlet port formed therein, a nest of tubes located within said shell so as to form a steam space communicating with said inlet, an air off-take having its inlet well within the nest of tubes, baffles located within said nest, so arranged that condensate collected on all the baffles is caused to pass through a portion of said steam space and that non-condensable gases are directed to said air off-take.
11. In a condenser, a shell, a nest of tubes, an air off-take extending within the nest of tubes, and baffles within the nest of tubes arranged in directions corresponding to the natural path of steam flow to the air offtake.
12. In a condenser, a shell, a nest of tubes, a steam space surrounding the tubes, an air offtake extending within the nest of tubes, and condensate baffles within the nest of tubes arranged in the direction corresponding to the natural path of steam flow from the steam space to the air offtake.
13. In a condenser, a shell, a nest of tubes, a steam space surrounding the tubes, an air offtake within the nest of tubes, and condensate baffles within the nest of tubes arranged in the direction corresponding to the natural path of steam flow from the steam space to the air offtake and adapted to collect condensate and discharge it into the steam space.
14. In a radial flow condenser, the combination of a shell, a nest of tubes within the shell and eccentrically related thereto in order to define a crescent-shaped steam space between the tube nest and the shell, air offtake means extending within the nest of tubes, and baffle plates radiating from the region of the inlet of the offtake means and defining converging passages for condensable and non-condensable fluids.
15. In a radial flow condenser, the combination of a substantially cylindrically-shaped shell, an eccentric nest of tubes therein and defining with the shell a crescent-shaped steam space, air offtake means extending within the nest of tubes, and baffle plates arranged between the tubes and extending from the region of the inlet of the air offtake means, said baffles adapted to discharge sheets of condensate through which some of the condensable and non-condensable fluids must flow.
16. In a radial flow condenser, the combination of a cylindrically-shaped shell, an eccentric nest of tubes therein defining with the shell a crescent-shaped steam space, air offtake means entering the nest of tubes, baffle plates radiating from the region of the inlet of the air offtake means and dividing the nest of tubes into converging groups, the upper baffles converging toward the inlet of the air offtake means and adapted to discharge sheets of condensate on the baffle plates diverging from said air inlet whereby the temperature of the air is lowered before its withdrawal.
17. In a radial flow condenser, the combination of a substantially cylindrically-shaped shell, a nest of tubes eccentrically disposed therein to define with the shell a crescent-shaped steam space, air offtake means extending within the nest of tubes, a pair of baffle plates extending within the tubes and with their lower edges below the inlet of the air offtake means and defining converging condensate shed surfaces, a pair of baffle plates below the first pair and having diverging shed surfaces adapted to receive condensate from the surfaces of the first pair whereby air is cooled before entering the outlet means, another pair of baffle plates arranged between the upper pair and

the lower pair and having diverging condensate shed surfaces whereby condensate is discharged at the outer edges, the condensate discharged from the outer edges of the intermediate pair of baffles and the lower pair of baffles adapted to form sheets of condensate to assist in condensation of steam.

In testimony whereof, I have hereunto subscribed my name this 29th day of September, 1917.

RAYMOND N. EHRHART.
